(57) **CLAIM**

The ornamental design for an outdoor tossing game, as shown and described.

DESCRIPTION

FIG. 1 is a front, left perspective view of an outdoor tossing game comprised of a target and a launch pad wherein the launch pad is attached to the target;

FIG. 2 is a right rear perspective view thereof;

FIG. 3 is a front perspective view thereof;

FIG. 4 is a rear bottom perspective view thereof;

FIG. 5 is a right side elevational view thereof;

FIG. 6 is a front side view thereof;

FIG. 7 is a rear side view thereof;

FIG. 8 is a front, left perspective view of the outdoor tossing game with the launch pad removed from the target;

FIG. 9 is a rear right perspective view thereof;

FIG. 10 is a front perspective view thereof;

FIG. 11 is a rear perspective view thereof;

FIG. 12 is a right side view thereof;

FIG. 13 front side view thereof;

FIG. 14 is a rear side view thereof; and,

FIG. 15 is a right side elevational view of the outdoor tossing game with the target in a folded state.

The broken lines shown in the drawings depict portions of the outdoor tossing game that form no part of the claimed design.
